MOISTENING MECHANISM FOR ROTARY
DUPLICATING MACHINESHenry P. Keil, Chicago, Ill., assignor to The
Fixture Hardware Corporation, Chicago, Ill., a
corporation of Illinois

Application April 24, 1952, Serial No. 284,153

9 Claims. (Cl. 101—132.5)

1

The present invention is directed to improvements in a duplicating machine wherein copy sheets are moistened on one face with a solvent liquid and then pressed against a master sheet which has the material to be copied printed thereon in reverse with hectograph ink. In machines of this character it is customary to mount the master sheet on the drum by means of a suitable gripping device and to press the copy sheet against the master sheet on the drum by means of a small resilient pressure roller. The copy sheets are fed between two feeding rollers which are intermittently operated from the drum and one of the feeding rollers has its surface moistened with the solvent liquid by means of a roller which runs in a trough containing a supply of the solvent liquid and a second roller which transfers the solvent from the roller in the trough to the moistening roller.

In machines of this character it is necessary that the roller surfaces remain truly cylindrical in order to obtain the best copies. If a roller becomes flattened it will adversely affect the distribution of the solvent to the copy sheet. It is the purpose of my invention to provide a novel construction for supporting and controlling the several small rollers which moisten and advance the copy sheet to the drum and press it against the drum, whereby the rollers are brought into contact with each other only when the machine is operating and whereby they may be separated from each other in a simple fashion whenever a particular run of copies has been completed.

It is also a purpose of this invention to provide a novel assembly of the moistening rollers in combination with a drum cam for intermittently driving the rollers, which combination reduces the shock of engaging the cam with the driving wheels that are provided on the transfer roller of the moistening group so as to make the drum easier to turn and to make the driving wheels self adjusting with respect to the cams on the drum.

It is also a purpose of the invention to provide an improved means for supplying liquid to the trough or fountain in which one of the rollers operates, which facilitates cleaning of the liquid inlets and maintenance of the moistening mechanism.

The nature and advantages of this invention will appear more fully from the following description and the accompanying drawings wherein a preferred embodiment of the invention is shown. It should be understood however, that the drawings and description are illustrative only

and are not intended to limit the invention except insofar as it is limited by the claims.

In the drawings:

Figure 1 is a plan sectional view taken substantially on the line 1—1 of Figure 3 with part of the drum being left in place to show its relation to the operative mechanism and the remainder of the drum being broken away to show the parts beneath it;

Figure 2 is an enlarged sectional view taken substantially on the line 2—2 of Figure 1;

Figure 3 is a sectional view taken on the line 3—3 of Figure 1, showing the parts in a changed position from that shown in Figure 1;

Figure 4 is a fragmentary sectional view taken on the line 4—4 of Figure 1;

Figure 5 is a fragmentary detailed view partly in section looking at the left hand end of Figure 1, but showing the connection between the solvent bottle holding unit and the tubes which lead to the liquid trough in cross section;

Figure 6 is a sectional view taken substantially on the line 6—6 of Figure 5;

Figure 7 is a view in side elevation of a duplicating machine embodying my invention, looking at the machine from the left hand end of Figure 1; and

Figure 8 is a view in side elevation of the duplicating machine, looking at the right hand end of Figure 1.

Referring now to the drawings and in particular to Figures 1 to 4 inclusive, my invention is shown as embodied in a duplicating machine which comprises supporting side frames 10 and 11 and a feed tray at 12 on which copy sheets may be advanced. A drum 13 is mounted between the side frames 10 and 11 and has its shaft 14 journaled for rotation in the side frames. The drum is rotated by a handle 15 which is shown most clearly in Figure 8 of the drawings. Any suitable master sheet clamping mechanism such as that shown in my prior application, Serial No. 760,538, filed July 12, 1947, for Duplicating Apparatus, Letters Patent No. 2,597,304, dated May 26, 1952, may be used for securing a master sheet to the drum 13. A portion of this clamping mechanism is illustrated at 16 in Figure 3 of the drawings. The details of this clamping mechanism are not illustrated herein as they form no part of the present invention. A pressure roller 17 is utilized to press copy sheets against a master sheet secured on the drum 13. In order to feed the copy sheets to the drum and to supply them with a suitable solvent, I employ a lower copy sheet feeding

roller 18, a moistening and feeding roller 19, a fountain roller 20 and a transfer roller 21. The fountain roller 20 runs in a fountain or trough 22 which is supported between the side frames 10 and 11 in front of the drum 13 and over an upwardly inclined guide lip 12a on the copy sheet feeding platform 12.

The construction and arrangement of the supporting mechanisms for the several rollers just described is such that when the parts are in the resting position, as illustrated in Figure 2 of the drawings, the several rollers are spaced apart and entirely free of each other so that there is no tendency for one roller to flatten another even though they may be left without operation for a long time. A simple mechanism is provided whereby the several rollers may be moved into operative engagement with each other under suitable pressure and the pressure roller 17 may be brought into pressure engagement with the drum 13 by operating a hand lever 23 which is shown at the right hand end of Figure 1 and in the lower right hand corner of Figure 8. Preferably the transfer roller 21 is a metal roller with a hard surface that is finely grooved for distributing the liquid solvent on the moistening roller 19. It is particularly important that this hard roller be prevented from resting on the relatively soft synthetic rubber rollers 19 and 20, as such engagement would form depressions in the softer rollers.

According to my invention I mount two cams 24 and 25 on the drum at the opposite ends thereof. These cams are adapted to engage driving wheels 26 and 27 which are provided on the ends of the roller 21. In this way the rotation of the drum will impart to the roller 21 a limited rotation while the cams 24 and 25 are in engagement with the wheels 26 and 27. The roller 21 is supported at its ends by two bars 28 and 29 and these bars are mounted on the ends of the trough 22 in such a fashion that they have a limited movement up and down and are yieldably urged toward the drum by springs 30 and 31. The construction by which this mounting of the roller 21 is achieved is the same at both ends of the trough 22 and is best illustrated in detail by Figure 4 of the drawings.

Referring now to Figure 4 of the drawings, the bar 29 is shown as provided with an elongated aperture 32 and a slot 33 to receive two mounting pins 34 and 35 that are threaded into the end portion 22a of the trough 22. This end portion 22a has two slots 36 and 37 facing toward the rollers 20 and 19 respectively. A spring 38 is seated in the slot 36 and yieldingly presses a bearing sleeve 39 on the shaft 20a of the roller 20 upwardly. The roller 19 has a bearing sleeve 40 on its shaft 19a and this bearing sleeve is guided in vertical movement by the slot 37. A pin 41, seated in the end 22a of the trough, limits the downward movement of the bearing 40 in the slot 37. The roller 21 has its shaft 21a mounted in a bearing sleeve 42 that is seated in the bar 29. The mounting of the rollers at the other end 22b of the trough is the same as that shown in Figure 4, and the bar 28 is mounted by pins 34 and 35 at the end 22b of the trough in the same manner as the bar 29 is mounted. The parts are shown in Figure 4, in the position that they occupy when the three rollers 19, 20 and 21 are separated from each other and the roller 18 is lowered out of contact with the roller 19. This is the resting position of the mechanism and is the same position as that shown in Figure 2 of the drawings. The spring 31 is seated in a recess 43 in the end of

the bar 29 and bears against a shoulder 45 that is formed on the end portion 22a of the trough 22. A like shoulder 44 forms a stop for the spring 30 which is seated in the end of the bar 28.

When the cams 24 and 25 engage the wheels 26 and 27 on the transfer roller 21, the bars 28 and 29 can move endwise against the pressure of the springs 30 and 31. Also the bars have a limited movement up and down so as to permit the roller 21 to seat properly on the rollers 19 and 20.

Figure 2 illustrates the position of the parts when the rollers 17 and 18 are lowered away from contact with the drum 13 and the roller 19 respectively. The feeding roller 18 is supported on two arms 46 and 47 that are pivoted on a cross tie rod 48 that extends between the side frames 10 and 11. These arms have recesses at their free ends to receive bearings 50 that are journaled on the ends of the shaft 18a of the roller 18. The arms 46 and 47 are constructed alike except that one is for the left hand side and the other is for the right hand side of the machine. The roller 17 has bearings 51 journaled on the ends of its shaft 17a and these bearings fit in recesses 52 that are provided in lever arms 53 which support the roller 17. The lever arms 53 are pivoted to the side frames 10 and 11 by pivot pins 54 that extend into bosses 55 provided on the side frames. The lever arms 53 have adjustable stop members 56 at their lower ends and these stop members bear against eccentric cams 57 that are fixed on a shaft 58. The shaft 58 is journaled in the side frames 10 and 11. The hand lever 23 is affixed to one end of the shaft 58. At the other end of the shaft 58, a bracket 59 is secured to the side frame 10 and is provided with lugs 60 and 61 which are positioned to engage a pin 62 that is fixed on the cam 57 that is adjacent to the side frame 10. The pin 62 limits the movement of the cams 57 to approximately 180 degrees. When the pin 62 engages the lug 60, the roller 17 is raised into pressure engagement with the drum 13. When the pin 62 is engaged with the lug 61, the roller 17 is lowered away from the drum 13 as illustrated in Figure 2.

In order to apply operating pressure of the roller 18 against the roller 19, I provide a spring 63 between a pivoted block 64 on each lever arm 53 and a pivot block 65 on each arm 47. The springs 63 yieldingly press the arms 47 upwardly so as to cause the roller 18 to engage the roller 19 and lift it until it contacts the roller 21 and lifts the roller 21 so as to move the bars 28 and 29 upwardly against the heads of the pins 35. This is the position illustrated in Figure 3 of the drawings. It is obvious that when the parts are in this position, engagement of the cams 24 and 25 with the wheels 26 and 27 will force the roller 21 against the roller 20 so that the rotation imparted to the roller 21 will also cause rollers 20 and 19 to rotate to feed and moisten a copy sheet that is fed between the rollers 18 and 19. When the cams 57 are moved to allow the levers 53 to lower the roller 17 away from the drum, this relieves the pressure on the springs 63 so that the arms 46 and 47 may drop and allow the roller 18 to separate from the roller 19. The roller 19 will drop down until its bearing 40 rests on the pins 41 and the roller itself is spaced from the roller 21. The roller 21 is then free to drop with its bars 28 and 29 and the springs 30 and 31 move the bars 28 and 29 endwise to separate the rollers 20 and 21.

The pressure of the roller 21 against the roller

29 when the cams 24 and 25 engage the wheels 26 and 27 will depress the roller 21 against the springs 33 but as soon as the pressure on the roller 21 ceases, the roller 20 will be moved up by the springs 33. The engagement of the cams 24 and 25 with the wheels 26 and 27 exerts a downward force on the wheels and on the roller 21 sufficient to overcome the friction of the bars 28 and 29 against the heads of the pins 34 and 25 so that during the driving movement of the roller 21, the roller and its bars 28 and 29 are, in effect, floating under the horizontal resilient pressure of the springs 30 and 31 and the upward resilient pressure from the roller 19. This floating action allows the rollers to adjust themselves to each other and reduces the drag on the rotation of the drum to a minimum.

The liquid trough 22 has a liquid inlet opening in the end 22a. This opening is illustrated at 69 in Figures 2 and 6. A drain opening 67 is provided below the level of the opening 68. These two openings are utilized to fill and drain the trough 22. A pipe nipple 68 is threaded into the trough end 22a and extends outwardly through the adjacent side frame 10 of the machine. A similar pipe nipple 69 is threaded into the trough end wall 22 around the opening 67. These pipe nipples are utilized to removably mount a valved bottle holder 70. The bottle holder 70 has seats 71 and 72 for the ends of the nipples 68 and 69 and sealing rings 73 of a suitable resilient material such as neoprene rubber, are provided on the nipples to releasably secure them and seal them in the recesses 71 and 72. The bottle holder 70 is further secured against displacement by the provision of a laterally extending arm 74 thereon which is fastened by a screw 75 to the side frame 10. It is believed to be evident that upon removal of the screw 75, the bottle holder 70 can be pulled off the nipples 68 and 69 so as to make it easy to clean out the inlet and outlet openings for the trough 22.

The several rollers 17-21 are easily removed for cleaning or replacement. When the rollers 17 and 18 are in the lowered position shown in Figure 2, they can be lifted out easily. In order to remove the rollers 19, 20, and 21, the pins 34 and 35 can be removed, after which it is a simple matter to lift the rollers 19 and 20 out of the trough in portions 22a and 22b. The bars 28 and 29 slide off the ends of the shaft 21a. The trough 22 can be completely removed by removing bolts 75 that secure the trough onto brackets 76 that are secured to the side frames 10 and 11 by screw bolts 77.

It is believed that the nature and advantages of my invention will be apparent from the foregoing description.

Having thus described my invention, I claim:

1. In a duplicating machine, a supporting frame having a master sheet holding drum rotatably mounted in the frame and having a pressure roller for pressing copy sheets against the drum, a liquid trough mounted in the frame adjacent to the drum, a first roller supported in the trough, a second roller alongside the trough, end portions on the trough, the second roller having bearings mounted for movement up and down on said end portions, a third roller beneath the second roller, spring means yieldingly urging the third roller upwardly and causing it to support the second roller above its lower limit of movement with respect to the trough, a transfer roller above the wall of the trough between the first roller and the second roller, means

mounting the transfer roller for movement laterally toward and away from the first roller, said mounting means holding the transfer roller spaced above the second roller when the second roller is at its lower limit of movement with respect to said end portions, said mounting means including stops limiting the upward movement of the transfer roller when the second roller is moved up against it by the third roller.

2. In a duplicating machine, a supporting frame having a master sheet holding drum rotatably mounted in the frame and having a pressure roller for pressing copy sheets against the drum, a liquid trough mounted in the frame adjacent to the drum, a first roller supported in the trough, a second roller alongside the trough, end portions on the trough, the second roller having bearings mounted for movement up and down on said end portions, a third roller beneath the second roller, spring means yieldingly urging the third roller upwardly and causing it to support the second roller above its lower limit of movement with respect to the trough, a transfer roller above the wall of the trough between the first roller and the second roller, means mounting the transfer roller for movement laterally toward and away from the first roller, spring means urging the transfer roller away from the first roller, said mounting means holding the transfer roller spaced above the second roller when the second roller is at its lower limit of movement with respect to said end portions, said mounting means including stops limiting the upward movement of the transfer roller when the second roller is moved up against it by the third roller.

3. In a duplicating machine, a supporting frame having a master sheet holding drum rotatably mounted in the frame and having a pressure roller for pressing copy sheets against the drum, a liquid trough mounted in the frame adjacent to the drum, a first roller supported in the trough, a second roller alongside the trough, end portions on the trough, the second roller having bearings mounted for movement up and down on said end portions, a third roller beneath the second roller, spring means yieldingly urging the third roller upwardly and causing it to support the second roller above its lower limit of movement with respect to the trough, a transfer roller above the wall of the trough between the first roller and the second roller, means mounting the transfer roller for movement laterally toward and away from the first roller, spring means urging the transfer roller away from the first roller, said mounting means holding the transfer roller spaced above the second roller when the second roller is at its lower limit of movement with respect to said end portions, said mounting means including stops limiting the upward movement of the transfer roller when the second roller is moved up against it by the third roller, and manually operable means for holding the third roller down out of contact with the second roller.

4. In a duplicating machine, a supporting frame having a master sheet holding drum rotatably mounted in the frame and having a pressure roller for pressing copy sheets against the drum, a liquid trough mounted in the frame adjacent to the drum, a first roller supported in the trough, a second roller alongside the trough, end portions on the trough, the second roller having bearings mounted for movement up and down on said end portions, a third roller beneath the second roller, spring means yieldingly urging the

third roller upwardly and causing it to support the second roller above its lower limit of movement with respect to the trough, a transfer roller above the wall of the trough between the first roller and the second roller, drive wheels fixed on the ends of said transfer roller, cams on the drum positioned to engage the wheels and rotate the transfer roller during a portion of each revolution of the drum, means mounting the transfer roller for movement laterally toward and away from the first roller, said mounting means holding the transfer roller spaced above the second roller when the second roller is at its lower limit of movement with respect to said end portions, said mounting means including stops limiting the upward movement of the transfer roller when the second roller is moved up against it by the third roller.

5. In a duplicating machine, a supporting frame having a master sheet holding drum rotatably mounted in the frame and having a pressure roller for pressing copy sheets against the drum, a liquid trough mounted in the frame adjacent to the drum, a first roller supported in the trough, a second roller alongside the trough, end portions on the trough, the second roller having bearings mounted for movement up and down on said end portions, a third roller beneath the second roller, spring means yieldingly urging the third roller upwardly and causing it to support the second roller above its lower limit of movement with respect to the trough, a transfer roller above the wall of the trough between the first roller and the second roller, drive wheels fixed on the ends of said transfer roller, cams on the drum positioned to engage the wheels and rotate the transfer roller during a portion of each revolution of the drum, means mounting the transfer roller for movement laterally toward and away from the first roller, spring means urging the transfer roller away from the first roller, said mounting means holding the transfer roller spaced above the second roller when the second roller is at its lower limit of movement with respect to said end portions, said mounting means including stops limiting the upward movement of the transfer roller when the second roller is moved up against it by the third roller.

6. In a duplicating machine, a supporting frame having a master sheet holding drum rotatably mounted in the frame and having a pressure roller for pressing moistened copy sheets against the drum, a liquid trough mounted in the frame adjacent to the drum, feeding and moistening rollers for transferring liquid from the trough to a copy sheet and advancing the sheet to the drum, inlet and outlet nipples projecting from one end of the trough through the frame, a valved bottle holder fixed to the frame and having lateral seats for said nipples into which the nipples are slidable, sealing rings on the nipples, and means to secure the holder to the frame.

7. In a duplicating machine, a supporting frame having a drum rotatably mounted in the frame and having a pressure roller mounted in the frame for pressing copy sheets against the drum, means for moistening and feeding copy sheets to the drum and pressure roller comprising a liquid trough mounted in the frame adjacent to the drum, a liquid supply roller positioned in the trough, a transfer roller positioned between the supply roller and the drum and spaced laterally and above the liquid supply roller and

8. the trough, a feed and moistening roller spaced laterally from the supply roller toward the drum and below the transfer roller, means mounting the feed and moistening roller for movement up and down into and out of engagement with the transfer roller, a second feed roller spaced below the feed and moistening roller and movably mounted in said frame for up and down movement, means operable to raise the second feed roller to bring it in contact with the feed and moistening roller and to move the last named roller into engagement with the transfer roller, movable supports for the ends of the transfer roller including spring means urging the transfer roller away from the liquid supply roller toward the drum, drive wheels on the ends of the transfer roller and cams fixed to the drum at the ends thereof and positioned to engage the wheels as the drum rotates and force the transfer roller into driving engagement with the liquid supply roller against the pressure of the springs.

9. In a duplicating machine, a supporting frame having a drum rotatably mounted in the frame, and a pressure roller for pressing copy sheets against the drum, a liquid trough mounted in the frame adjacent to the drum, a roller in the trough, said roller having bearings at the ends and said trough having slots in the ends thereof in which said bearings will move up and down, springs in said slots supporting said bearings, said trough having end portions extending laterally toward the drum outside the trough, slots in said end portions, a second roller between the trough and the drum having bearings at its ends movable up and down in the slots in said end portions, a transfer roller above the first named rollers and adapted to engage both of them to transfer liquid from the roller in the trough to the second roller, laterally movable supporting means mounting the transfer roller for movement into and out of engagement with the roller in the trough, spring means urging said supporting means in a direction to hold the transfer roller out of engagement with the roller in the trough, means on the drum operable as the drum rotates to move the transfer roller into engagement with the roller in the trough during a portion of each rotation of the drum, a sheet feeding roller movably mounted in the frame and normally spaced below the second roller, and means to move the sheet feeding roller upwardly against the second roller and operable to raise the second roller into engagement with the transfer roller.

10. In a duplicating machine, a supporting frame having a drum rotatably mounted in the frame, and a pressure roller for pressing copy sheets against the drum, a liquid trough mounted in the frame adjacent to the drum, a liquid feed roller in the trough, bearings at the ends of said roller supported by the ends of said trough, said trough having end portions extending laterally toward the drum outside the trough, a second roller between the trough and the drum having bearings at its ends, the bearings being mounted for up and down movement in said end portions, a transfer roller above the two first named rollers and adapted to transfer liquid from the feed roller to the second roller, bars extending transversely of the trough at the ends of said transfer roller, the transfer roller being journaled for rotation in said bars, means mounting said bars for limited movement toward and away from the drum, springs urging the bars toward the

drum normally to hold the transfer roller spaced from the liquid feed roller, a sheet feeding roller spaced below the second roller and movably mounted in the frame for vertical movement to engage the second roller and lift it, manually operable means for raising the sheet feeding roller and the second roller to bring the second roller into engagement with the transfer roller, and means on the drum operable to move the transfer roller and said bars away from the drum 10 and bring the transfer roller into engagement

10 with the liquid feed roller during a portion of each rotation of the drum.

HENRY P. KEIL.
